UNITED STATES PATENT OFFICE.

RALPH E. SMITH AND ROY J. ARNOLD, OF GALION, OHIO, ASSIGNORS TO THE GALION METALLIC VAULT COMPANY, OF GALION, OHIO, A CORPORATION OF OHIO.

DUMP BODY.

Application filed April 29, 1927. Serial No. 187,664.

Our invention relates to dump bodies.

It is the object of our invention to provide a dump body which will automatically dump when loaded and when released.

5 It is a particular object of our invention to provide a construction that will be self contained and rigid to prevent any warping of the supporting mechanism which will throw the tilting and unloading mechanism out of alignment so as to prevent it properly functioning. It is a further object to provide the supports for the tilting mechanism of such character that they will serve the purpose of tying the chassis frame together.

10 15 It is an additional object of our invention to provide the combination of a dump body supported on the chassis frame indirectly. It is a further object to provide an arrangement by which the supporting brackets for the dump body and the points of connection of the brackets with the cross rods of the chassis frame are all inside of the chassis frame and inside of a supplementary frame thereby protecting the brackets and preventing 20 25 injury to persons who may be adjacent to the mechanism when it is operating.

Referring to the drawings,

Fig. 1 is a side elevation of the complete mechanism;

30 Fig. 2 is a rear elevation thereof;

Fig. 3 is a detail side elevation of a supporting bracket and the associated supporting mechanism, the supporting mechanism being shown in section;

35 Fig. 4 is a section on the line 4—4 of Fig. 1 looking in the direction of the arrows;

Fig. 5 is a front elevation of the supporting leg.

40 Referring to the drawings in detail, 1 represents a chassis frame which is connected together by a straight tube or rod 2 mounted in depending side plates 3 carried by the side members 4 of a supplementary frame which is mounted upon the chassis frame 1.

45 Thus a unitary construction is provided by which the supplementary frame 4 tied together by the transverse angle members 5 and 6 is provided carrying the depending side plates 3 within the chassis frame and connected together by the supporting bolts or rods 2, 7, and 8, rods 7 and 8 being kicked up centrally as at 9 and 10 to provide suitable clearance and adequate strength of the parts. The supplementary side members 3

are bolted to the supplementary frame 4 by 55 the bolts 11 and are spaced by the spacing blocks 12. The dump body 13 has connected to its side rails 14 on either side thereof a bracket consisting of a forwardly disposed downwardly extending vertical frame member 15 terminating in a jaw 16 which rocks upon the transverse rod 8. A second depending member 17 extends downwardly spaced from the member 15 and somewhat rearwardly at the bottom so that its general 60 direction is diagonal. This member 17 terminates in a jaw 18 riding upon the rod 7. The two jaw portions are connected together by a web 19. A second web 20 connects the jaw 18 with a jaw 21 which is 65 formed on the end of a depending diagonally disposed arm 22. From either side of the jaw 21 extends an arm having a U bolt 23 which extends around the bottom of the transverse rod 2 on which the jaw 21 is 70 75 adapted to be mounted and with which it engages when the body is in dumping position.

These two side frame members are connected together by crossed diagonally disposed brace rods 24 and 25. These cross frame members are connected to eyes 26 on the brackets. If it is desired to maintain the body in elevated position the stiff leg 27 is provided pivoted at 28. This leg is provided on either side of the body and the arms of the legs are joined together by a rod 29 to which is connected the usual chain 30. The spring 31 and the chain 32 are connected to the supplementary frame 4 and body 13. 80 85 The rod 29 is placed behind the shoulder 33 on the supplementary frame when the body is in its elevated position. The lever 46 will unseat the rod 29 through the chain connection 30.

90 The dump body is provided with the usual rear tail gate, the exact details of which are not important.

95 The forward end of the body is provided with a transverse rod known as a locking rod 34 engaged by a locking head 35 pivoted at 36 on the supplementary frame. A rearwardly extending arm 37 is also provided mounted on the frame to which is pivoted a lever 38 having an unlocking plunger 39 passing through the angle iron support 40 to the front end of the body and adapted to engage with the locking head 35 to un-

lock it against the resistance of the spring 41 which normally maintains the locking head 35 in locking position, such spring being supported at its free ends by the 5 bracket 42 mounted on the cross frame member 40. This lever 38 and bolt 39 are actuated by the pitman 43 connected to a lever 44 pivoted on the cab frame member 1. This lever 38 and bolt 39 are actuated by the 10 pitman 43 connected to a lever 44 pivoted on the cab frame or floor board at 45. The lever 44 terminates in a handle 46 adjacent the driver's seat 47. Thus the body can be unlocked from the driver's seat and as the 15 weight of the load is greater to the rear of the pivotal support on the rod 8 than in front of the pivotal support the body automatically tilts rearwardly first bringing the jaw 18 on the rod 7 and then the jaw 21 on 20 the rod 2 so that the load dumps, the tail gate being opened up automatically in the usual manner to permit of the discharge of the load.

Method of operation.

25 When the lever 46 is pushed forwardly by the operator on the seat 47 the bolt 39 moves the locking head 35 forwardly against the resistance of the spring 41 disengaging the 30 head of the locking head 35 from the latching rod 34 on the body thereby releasing the body. The weight being greater on the rear of the body with respect to the rod 8 than on the forward part of the body, the body 35 automatically tilts rearwardly until the jaw 18 engages with the rod 7. Then the jaw 16 lifts off of the rod 8 and the body continuing in its rearward movement is finally brought to rest by the engagement of the 40 jaw 21 with the rod 2 and the engagement of the dump body with the cross frame 5. As soon as the load is dumped, the body being heavier when empty in front of the rod 2 than to the rear thereof, the body will 45 automatically return to its initial position. It will be prevented from continuing its forward arcuate movement by the restraining effect of the U bolts 23 which pass beneath the rod 2. In its return movement 50 the brackets first engage through the jaws 18 of the rod 7 and then lift the jaws 21 off of the rod 2 and finally reengage the rod 8 through the jaw 16.

The cross frame members 24 and 25 rigidly 55 tie these supporting brackets together and prevent any warping or non-alignment of the parts so that the brackets always are accurately positioned with respect to the supplementary side frame members 3, the 60 cross rods 2, 7 and 8 and the dump body supported by the brackets.

The abuse imparted to a structure of this sort is extreme. The loads are dumped into the body usually from an elevation from a 65 steam shovel dipper bucket and not only con-

tain earth but often times rock or large pieces of rock. The operators operate the vehicles in the worst kind of terrain where jars and twisting strains of all sorts are customary and common and necessary and 70 the operators themselves are usually of the type that is largely unskilled and neglectful of equipment, so that the equipment must be self sufficient and self contained and so rigid and strong that ordinary usage will not 75 throw the parts out of alignment.

This equipment is used largely by contractors to whom time is of the essence and any breakdown of equipment would be extremely serious in causing failure to perform 80 the contract on time.

Hence it is essential to have a construction that can not get out of alignment, that can not come apart, and a construction in 85 which any accumulation of dirt, mud, small parts of rock and the like will not injure.

It is further necessary to have the entire dump body unit consisting of the dump body, the interlocking and interlocked brackets and the supplementary frame, so 90 constructed as to be able to drop them as a unit on to the chassis frame.

This type of equipment is manufactured by dump body manufacturers who sell their dump bodies and associated equipment to those who either own the chassis frame or those who will assemble the chassis frame and dump body for sale to others. The truck with the chassis frame is one unit of manufacture and the equipment explained in this specification is another item. Hence 95 it is essential that the two items be so constructed that they are independent of one another and can be assembled by the easiest method possible. Hence the dump body, supplementary frame, brackets, and associated mechanism have been constructed as a single self contained unit adaptable to any proper form of chassis frame.

100 It will be understood that we desire to comprehend within our invention such modifications as may be necessary to adapt it to varying conditions and uses.

Having thus fully described our invention, 105 what we claim as new and desire to secure by Letters Patent is:—

1. In combination, a dump body, a pair of spaced brackets, means to brace said brackets with respect to one another and to rigidly tie them together as a unitary support for 110 said body, a plurality of spaced support engaging jaws on said brackets, a supplementary frame, inwardly disposed depending, supporting and guarding plates mounted on either side of said frame, supporting rods connected therebetween adapted to engage 115 with said jaws on said brackets and U bolts spaced from a pair of said jaws adapted to pass around one of said supports to prevent 120 the brackets from being detached entirely 125

from the supports and limiting the movement of the body with the brackets in one direction.

2. In combination, a dump body, a pair of spaced brackets, means to brace said brackets with respect to one another and to rigidly tie them together as a unitary support for said body, a plurality of spaced support engaging jaws on said brackets, a supplementary frame, inwardly disposed depending, supporting and guarding plates mounted on either side of said frame, supporting rods connected therebetween adapted to engage with said jaws on said brackets, **U** bolts 10 spaced from a pair of said jaws adapted to pass around one of said supports to prevent the brackets from being detached entirely from the supports and limiting the movement of the body with the brackets in one 15 direction, and a chassis frame for supporting said supplementary frame so arranged as to receive said supporting and depending members within the chassis frame.

3. In combination, a dump body, brackets 25 depending from said dump body on either side thereof, a frame, a plurality of supports mounted on the frame for engaging with said brackets consisting of a forward support and an intermediate support and a rear support, the intermediate support being an 30 elevation from the ground greater than the forward and rear supports which are on the same level, a plurality of engaging jaws for said supports on said bracket members, said

jaws being so arranged that the intermediate 35 jaws are elevated above the forward jaws and the rear jaws above the intermediate jaws and the brackets being so attached to the dump body that when the body is loaded it will tend to dump and when it is empty it 40 will tend to return to its normal loading position.

4. In combination, a dump body, brackets depending from said dump body on either side thereof, a frame, a plurality of supports 45 mounted on the frame for engaging with said brackets consisting of a forward support and an intermediate support and a rear support, the intermediate support being an elevation from the ground greater than the 50 forward and rear supports which are on the same level, a plurality of engaging jaws for said supports on said bracket members, said jaws being so arranged that the intermediate 55 jaws are elevated above the forward jaws and the rear jaws above the intermediate jaws and the brackets being so attached to the dump body that when the body is loaded it will tend to dump and when it is empty it 60 will tend to return to its normal loading position and brace members connecting said frame members together to provide a rigid bracket support for the body.

In testimony whereof, we affix our signatures.

RALPH E. SMITH.
ROY J. ARNOLD.
